UNITED STATES PATENT OFFICE.

JOHN W. PEER, OF TROY, NEW YORK.

IMPROVEMENT IN ROPE MACHINERY.

Specification forming part of Letters Patent No. **23,486**, dated April 5, 1859.

To all whom it may concern:

Be it known that I, JOHN W. PEER, of Troy, in the county of Rensselaer and State of New York, have invented a new and useful Improvement in Rope-Making Machines; and I do hereby declare that the following is a full, clear, and exact description of the same, reference being had to the accompanying drawings, forming part of this specification, in which—

Figure 1 is a longitudinal vertical section of a horizontal rope-making machine with my improvements. Fig. 2 is a transverse vertical section of the same through the fliers. Fig. 3 is a longitudinal view of the laying-block, partly in section.

Similar letters of reference indicate corresponding parts in the several figures.

This invention consists in a certain novel and very simple method of conducting the strands from the bobbins to their respective flier-heads, whereby they are caused to draw with nearly equal freedom, and hence to have nearly the same tension, whether being supplied from the middle of or near the ends of their bobbins.

To enable others to make and use my invention, I will proceed to describe its construction and operation.

In the example of my invention represented in the accompanying drawings the fliers work in stationary bearings and the laying of the strands into rope is produced by the revolution of a flier carrying a bobbin on which the rope is taken up.

A A' B B' are stationary standards constituting the framing of the machine, the standards A A' containing the bearings for the strand-fliers D D, and those B B' the bearings for the laying-fliers C.

E E are stays connecting the standards A' and B.

F is the driving-shaft arranged to work in bearings in the standards A and B, and carrying two pulleys G and I, from the former of which two belts H H' pass round pulleys a a on the several strand-fliers for the purpose of driving the said fliers, and from the other I a belt J passes around a pulley b on the laying-flier, for the purpose of driving that flier. The laying-flier contains the capstans S S for taking up the rope as fast as it is laid, and conveying it to the bobbin or

reel (not shown) that is contained within the laying-flier. These capstans are driven by a suitable train of gearing carried by the flier and deriving motion through a belt R running from a pulley l on the shaft F to a pulley m, which works on the journal of the flier C and carries the first gear of the train.

The strand-bobbins K K are arranged to rotate on spindles whose axes coincide with the axis of revolution of their respective fliers. The strand-fliers have each a hole c in one of their side pieces or side rods d d, such hole being so arranged as to be opposite the middle of the length of the bobbin when the latter is in its place in the flier.

The strand h from the bobbin of each flier D is conducted over and around the outside of the opposite side rod or side piece d to that which contains the hole, and from thence across to and through the hole c, and from thence through an eye e on the flier-head, and through the hollow journal of the latter to the laying-block, as shown in Fig. 1.

To prevent the strand from dragging on the bobbin in passing from one side piece d to the other, guard-rods f f, arranged longitudinally of the flier, are attached to the flier-heads for the purpose of keeping clear of the bobbin the portion of the strand between the two side pieces d d. The operation of these guide-rods f f is illustrated in Fig. 2. By thus conducting the strand round the exterior of one side of the flier, and from thence to a hole or guide at the center of the opposite side, the strand is caused to draw more directly from the bobbin, as it is taken from near the ends thereof, than when it passes at once to a guide occupying a fixed position on the side of the flier, and from thence to the flier-head, as will be readily understood by reference to the upper flier, (shown in Fig. 1,) where it will be seen that though the strand is being taken from close to one head of the bobbin it is drawn almost directly therefrom instead of at a very oblique angle, as it would be in an ordinary flier.

L M is the laying-block made in two parts or pieces, one L of which has a conical end or face, in which grooves g g are provided for the reception of the strands h h. The other part M is simply a hollow cone fitted to the conical face of the part L. The last-mentioned part M is in the example of the improve-

ment represented in the drawings formed upon or attached to the hollow journal of the laying-flier C, through which the strands enter the said flier; but the said part M may be stationary in some forms of rope-machines. The piece L is bored from its back end concentrically with its conical face to fit to one end of a rod O, arranged in line with the center of the part M, the other end of which rod rests against the standard A' and is held in the proper line by a cross-head N, which is firmly attached to it and fitted to the stay-rods E E. The said piece L is fitted to the end of the rod O in such manner as to be capable of sliding longitudinally thereon to a limited extent, but prevented turning therein by slots *j* in the sides fitting to ears *k* on the rod, as shown in Figs. 1 and 2. It is also fitted to the rod so loosely as to be capable of a little lateral oscillation thereon. Between the said piece L and the cross-head N there is applied a spiral spring Q, coiled around the rod O, and this spring exerts its force to push the cone of the said piece L into the cone of the part M. The strands *h h* pass from their respective fliers between the cones of L and M and through the grooves *g g* of the piece L, which grooves must not be deep enough for the strands to bury themselves within them, as it is required that they shall be pressed be-

tween L and M by the spring Q. In case of any variation in the size of the strands in any part thereof the longitudinal movement permitted to the piece L by the spring Q and the lateral movement permitted to the said pieces L on the spindle permit the cone of the said piece so to adjust itself within the hollow cone of the part M as to provide a larger opening on the side on which the largest strand is presented and yet to make the said cone press just as tightly upon the smaller strands, so that the same degree of tension is at all times produced upon each strand at the laying-block notwithstanding any variations in size. The portion L of the laying-block will in a sun-and-planet machine rotate along with the fliers in their planetary motion.

What I claim as my invention, and desire to secure by Letters Patent, is—

Conducting the strands from their bobbins round the exterior of one side of the flier and from thence over guide-rods *f f* or their equivalents to and through a hole or guide *c* on the opposite side of the flier, substantially as and for the purpose herein set forth.

JOHN W. PEER.
